UNITED STATES PATENT OFFICE.

JAMES L. SCHOLL, OF POWELLSVILLE, NORTH CAROLINA.

AUTOMATIC HEAT CONTROL FOR TOBACCO ROOMS.

Application filed June 4, 1925. Serial No. 34,892.

To all whom it may concern:

Be it known that JAMES L. SCHOLL, a citizen of the United States of America, residing at Powellsville, in the county of Bertie 5 and State of North Carolina, has invented new and useful Improvements in Automatic Heat Controls for Tobacco Rooms, of which the following is a specification.

It is essential in drying or curing tobacco 10 that the temperature in the barn or room in which the operation is carried out be not permitted to fluctuate but be raised gradually as the tobacco is dried. The temperature of the barn or room should be initially 15 the same as the outside temperature when the curing or drying is begun and then be gradually increased at the rate of 1° F. per hour for from ninety-six to one hundred hours.

20 It is the object of the present invention, therefore, to provide an automatic heat control for tobacco drying rooms or barns for effectively securing a uniform increase throughout the prescribed period irrespec- 25 tive of the temperature of the exterior or surrounding air; and to provide, in such a control, heating elements and a tank for furnishing fuel to the same, together with thermostatically controlled means for permitting the flow of fuel to the heating elements, whereby the latter are actuated to 30 accomplish the purpose desired.

The invention comprises further features and combinations of parts to be hereinafter 35 set forth, shown in the drawings and claimed.

In the drawings:

Figure 1 is a view in elevation of the improved automatic heat control apparatus for 40 tobacco drying rooms constructed in accordance with the invention.

Figure 2 is a sectional view on the line 2—2 of Figure 1.

Figure 3 is a horizontal sectional view on 45 line 3—3 of Figure 1.

Figure 4 is a horizontal sectional view on line 4—4 of Figure 3, more clearly showing the construction of the thermostatically con-

trolled means which insures a strict control of the heat.

50 Figure 5 is a sectional view on line 5—5 of Figure 1.

Referring to the drawings, 1 designates an oil tank which may be any size, shape and construction and 2 denotes pipes or fuel conductors of which there may be as many as convenient to insure necessary heat for a tobacco drying room. The pipes extend radially and are connected to suitable burners 3 of conventional type which give off heat to 60 insure heating a tobacco drying room.

Rising from the bottom of the tank 1 and integrally connecting the top of the tank (which has a flanged filling opening 4 with a removable cap 5) is a guide tube 6 through 65 which a tube 7 is guided, a plate 8 being carried by the upper end of said tube. Depending from the plate or cross-piece 8 are rods 9 which pass through suitable guide openings 10 in the top of the tank, the lower ends 70 of said rods having slide valves 11 which are mounted in guides 12 of the adjacent ends of the pipes or conductors 2.

The valves 11 have elongated openings 13 and a plurality of small orifices or openings 75 14, the latter being below the former, the object being that when the valves are raised sufficiently to remove the openings 13 from registration with the pipes 2, one or all of the openings 14 may register with the pipes, 80 allowing a minimum amount of fuel or gasoline to enter the pipes 2 and thereby reach the burners. However, it is obvious that when the valves are lowered with the openings 13 in register with the pipes 2, a maximum supply of fuel or oil is allowed to enter the pipes and hence reach the burners.

85 The tank 1 is supported upon suitable standards 15 which rise from a base 16 and fastened to the base is an interiorly threaded cylinder 17 which supports a suitable crown gear wheel 18, there being ball bearings 19 between the gear wheel and the interiorly threaded cylinder, so that the crown gear wheel will rotate freely. The cylinder 17 90 has means, as indicated at 20, which pre-

vents upward movement of the crown wheel as it rotates. In other words, the crown gear wheel is permitted to rotate but not to move axially of the cylinder or axially of a movable cylinder 21.

The cylinder 21 has diametrically opposite ribs or keys 22 which engage in diametrically opposite grooves in the opening of the crown gear wheel 18, thereby causing the movable cylinder 21 to lower and at the same time rotate with the crown gear wheel. The lowering of the movable cylinder 21 is caused due to it being exteriorly threaded and engaging the interior threads of the cylinder 17. For instance, the rotating of the crown gear wheel rotates the movable cylinder 21 due to the rib and groove connections and since the movable cylinder 21 is capable of movement through the crown gear wheel, it will adjust vertically on account of its threaded connections with the cylinder 17.

The lower end of the tube 7 on its interior has a partition wall 23 and supported on antifrictional ball bearings 24 within a space or chamber 25 at the upper end of the movable cylinder 21 is a vessel or container of mercury 26. This vessel or container has a tubular extension 27 which has an exteriorly telescopically fitted tube 28 slidable over the extension 27 and being fitted movably in the lower end of the tube 8, whereby as the temperature of the room increases, the mercury in the container or vessel 26 will expand sufficiently to cause the tube 28 to rise and abut against the partition and hence raise the pipe or tube 7, and since the rods 9 are connected to the upper end of the tube 7, they will correspondingly move. Since the rods 9 are connected to the slide valves, as shown, the valves will adjust in order to regulate the registration of the openings 13 and 14 with the adjacent ends of said pipes 2.

Where the tubes 27 and 28 telescopically unite, an interiorly arranged tube of rubber or other suitable material is mounted, thus preventing any leakage of the mercury exteriorly of the vessel or container 26. Projecting from the cylinder 17 is a support 29 on which the casing of a suitable clockwork or timing mechanism 30 is supported. In this mechanism, the minute hand is dispensed with and a pinion 31 mounted upon the unit spindle 32 of the mechanism, this pinion meshing with the teeth of the crown gear wheel 18 so as to rotate the latter and thereby lower the cylinder 21 as the column of mercury increases in length. Thus, a more effective control of the fuel valves is had than would be the case were their operation dependent solely upon the expansion of the column of mercury. Therefore, the construction provides for the gradual increase in the temperature of the room or barn.

When the mercury in the container or vessel 26 expands, the rods 9 move upwardly and thereby move the valves upwardly which move the openings 13 out of register with the adjacent ends of the pipes, and thereby cut off the supply of kerosene to the burners. A contraction of the mercury in the vessel or container allows the tube or pipe 7 to lower and hence the rods will register the openings 13 of the slide valves with the adjacent ends of the pipes 2, permitting an increased flow of kerosene or other fuel to the burners, thereby causing the burners to send off a uniform supply of heat for the tobacco drying room.

The invention having been set forth, what is claimed is:

1. In an automatic heat control for tobacco drying rooms, the combination with a fuel tank having radiating pipes near its bottom with exteriorly disposed heating elements, of slide valves for adjacent ends of said pipes with maximum and minimum size openings registerable with said adjacent ends of the pipes, and thermostatically controlled means for governing the positions of the valves to register the maximum or minimum openings with the ends of the pipes to permit a general or minimum flow of fuel to the heating elements. 90

2. In an automatic heat control for tobacco drying rooms, the combination with a fuel tank having radial pipes with exteriorly disposed heating elements, of slide valves having maximum and minimum size openings registerable with adjacent ends of said pipes, means consisting of a vertically movable tube with operative connections with the valves for controlling the position of the valves whereby a general or minimum flow of fuel is permitted to reach the heating elements through the pipes, and thermostatically controlled means for actuating the vertically movable tube. 100

3. In an automatic heat control for tobacco drying rooms, the combination with a fuel tank having radiating pipes near its bottom with exteriorly disposed heating elements, of slide valves for adjacent ends of said pipes with maximum and minimum size openings registerable with said adjacent ends of the pipes, thermostatically controlled means for governing the positions of the valves to register the maximum or minimum openings with the ends of the pipes to permit a general or minimum flow of fuel to the heating elements, movable means for the support of the thermostatically controlled means, and a time mechanism for controlling said movable means to increase the temperature as desired. 110

4. In an automatic heat control for tobacco drying rooms, the combination with a fuel tank having radial pipes with exteriorly disposed heating elements, of slide valves hav- 130

ing maximum and minimum size openings registerable with adjacent ends of said pipes, means consisting of a vertically movable tube with operative connections with the valves 5 for controlling the position of the valves whereby a general or minimum flow of fuel is permitted to reach the heating elements through the pipes, thermostatically controlled means for actuating the vertically 10 movable tube, a vertically movable support for the thermostatically controlled means, and a time mechanism having operative gear connections with said vertically movable support for lowering the same and thereby increasing the temperature of the room in 15 a uniform manner.

In testimony whereof he affixes his signature.

JAMES L. SCHOLL.
